FIG. 1

FIG. 2

FIGURE 1 is a perspective view of one side of a reversible rug showing our new design; and

FIGURE 2 is a perspective view of the other side of the rug.

The characteristic feature of our design resides in the fanciful representation of a dog on one surface of the reversible rug, which feature is illustrated in FIGURE 1 of the drawing.

We claim:

The ornamental design for a reversible rug or similar article, substantially as shown and described.
